[57] CLAIM

The ornamental design for a chain shipping and dispensing container, as shown and described.

DESCRIPTION

FIG. 1 is an exploded perspective view of a chain shipping and dispensing container showing my new design; FIG. 2 is a bottom plan view thereof; FIG. 3 is an exploded perspective view of a second embodiment of FIG. 1; and, FIG. 4 is a bottom plan view of FIG. 3. The corresponding undisclosed views of first and second embodiments are identical to the views as shown in FIG. 1 and FIG. 3 respectively.

FIG. 1

FIG. 2

FIG. 3

FIG. 4
